UNITED STATES PATENT OFFICE

ANDREW J. SORENSEN, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed September 28, 1927. Serial No. 222,520.

My invention relates to railway traffic controlling apparatus, and particularly to apparatus of the intermittent inductive type involving inductors located at intervals in the 5 trackway and controlled by traffic conditions in advance for transmitting train governing impulses to moving trains.

The present application is a continuation in part of my copending application filed 10 July 21, 1927, Serial No. 207,401, for railway traffic controlling apparatus, in so far as the subject matter common to the two is concerned.

I will describe two forms of apparatus embodying my invention, and will then point out the novel features thereof in claims.

In the accompanying drawing, Fig. 1 is a diagrammatic view showing one form of apparatus embodying my invention. Figs. 20 2 and 3 are curves showing the magnetic and electrical characteristics of certain parts of the apparatus shown in Fig. 1. Fig. 4 is a diagrammatic view showing a modification of the apparatus shown in Fig. 1 and also 25 embodying my invention.

Similar reference characters refer to similar parts in Figs. 1 and 4.

Referring first to Fig. 1, the reference character A designates a magnetizable receiver located on a railway train and provided with a primary winding P and a secondary winding S. The train-carried apparatus also includes a relay G, an impedance C which as here shown is a magnet winding C, and a 35 manually operable acknowledging switch K comprising two normally open contacts 12 and 16.

The primary winding P is provided with a circuit which passes from a battery H or other 40 source of direct current, through wires 2 and 3, contact 4^a-4 of relay G, wire 5, primary winding P, wire 6, magnet winding C, and wire 7 to battery H. The circuit for the secondary S is from battery H, through 45 wires 2 and 3, contact 4^a-4-4^b of relay G, wire 8, winding of relay G, wire 9, secondary winding S and wire 10 to an intermediate point in primary winding P, then through the right-hand portion of the primary winding, wire 6, magnet winding C, and wire 7

to battery H. These circuits are normally closed, with the result that magnet winding C is energized. Winding C controls a valve D, which in turn controls the exhaust of air from a brake control pipe E. When magnet C is energized valve D is closed and no automatic application of the brakes occurs. When magnet C is de-energized, however, valve D opens to exhaust air from pipe E to atmosphere, and the resultant reduction of pressure in pipe E will then cause an automatic application of the breaks by virtue of suitable apparatus not shown in the drawing. 55

Located in the trackway are a plurality of inductors B, only one of which is shown in the drawing. Each of these inductors is provided with a winding L, the circuit of which may be opened and closed by a contact 18, which contact is usually controlled in accordance with traffic conditions in advance. 60 The inductors B co-operate with the train-carried receiver A in such manner that if the circuit for winding L is closed when the receiver passes over the inductor the reluctance of the receiver is not materially reduced, 65 whereas if the circuit for winding L is opened, the reluctance of the receiver A is materially reduced, due to the fact that the inductor substantially completes the magnetic circuit of the receiver. 70

The operation of the parts of the apparatus thus far described, is as follows: Normally, the primary and secondary circuits of the train-carried apparatus are closed, so that magnet C is energized and valve D is closed. 75 When the receiver passes over a trackway inductor, if contact 18 is closed the reluctance of the receiver core is not materially changed and no change occurs in the condition of the train-carried apparatus. If, however, contact 18 is open, the flux in the receiver core due to the primary winding P is momentarily increased, and this momentary increase of flux creates in the secondary winding S an electromotive force which opposes the electromotive force of battery H. As a result 80 there is produced, in the secondary circuit, a current impulse which opposes the current flowing in the secondary circuit from battery H, so that relay G is de-energized, with 85 90 95 100

the result that the contacts of this relay are opened, and remain open until suitable action is taken by the engineer as hereinafter explained. Magnet C then becomes de-energized, so that valve D opens to cause a 5 brake application.

In the foregoing description of the operation I have assumed that the engineer takes no action. If the trackway contact 18 is 10 opened, and if the engineer closes the acknowledging switch K just before the receiver passes over the inductor, an auxiliary circuit for relay G will be closed, which circuit passes from battery H, through wires 2 and 15, contact 16 of acknowledging switch 15 K, wire 17, winding of relay G, wire 9, secondary winding S, wire 10, right-hand section of primary winding P, wire 6, magnet C and wire 7 to battery H. Then when the receiver passes over the inductor, relay G will 20 momentarily open but will immediately close again because of the auxiliary circuit which I have just traced. The result will be that valve D remains closed and no automatic application of the brakes occurs. Acknowledging switch K will usually be controlled in 25 such manner that its contacts can be closed only for a limited period of time. If the engineer fails to close acknowledging switch K just before passing over the trackway inductor, and if contact 18 is opened so that an automatic application of the brakes occurs, 30 relay G can be again closed by manual operation of acknowledging switch K. The resulting closure of contact 16 will close the auxiliary circuit for relay G, and the closure of contact 12 will close the following circuit for primary winding P: from battery H, through wires 2 and 11, contact 12 of 35 acknowledging switch K, resistance 13, wires 14 and 5, primary winding P, wire 6, magnet C and wire 7 to battery H. Magnet C and relay G will therefore become 40 re-energized, and after relay G closes, these parts continue energized over their normal 45 circuits above described, even though switch K is restored to the position in which it is illustrated in the drawing. The brakes can 50 then be released by suitable manipulation of the apparatus controlled by pipe E.

With the apparatus thus far described, the receiver and the relay are more sensitive, that is, they are more easily operated upon passing inductors and other iron structures, directly after a re-set than after the receiver has passed a few inductors or other iron structures without de-energization of the relay G. This is due to hysteresis in the iron cores of the receiver and the relay, and the 55 purpose of the present invention is to provide means by which this effect of the hysteresis can be eliminated.

I will assume that the relay G has been 60 de-energized by an active trackway inductor, and that the engine equipment is about to be

re-set. Referring now to Fig. 2, since the receiver comprises a magnetic circuit with an air gap, the flux in the receiver core is always built up in the same way at re-set, namely, from a value very close to zero, represented by the point O, to a value represented by the point F₁ corresponding to the number of ampere turns used to energize the receiver. With the flux at the point F₁, I will assume that the receiver passes over an inductor in active condition, but that the engineer closes circuit controller K. As the receiver runs into its position in closed relation to the inductor, the receiver flux will increase to a value such as F₂, and when the receiver recedes from such position, the flux will not decrease to the value F₁, but due to the magnetic hysteresis of the iron, it will decrease to a value F₁¹, which is greater than F₁. If the receiver then passes another inductor under the same conditions, the flux will increase to a value F₂¹, which is slightly greater than the value F₂, and will then decrease to a value slightly greater than F₁¹. This process will be repeated every time an inductor is passed under the same conditions, except that the values within the groups F₁ and F₂, respectively, will tend to reach limiting values so that finally a point will be reached at which the flux will change between the same two values every time. The same action will result from inductors in the inactive condition, or from switch rails or other masses of iron located close to the path of the receiver A. As pointed out in describing the normal operation of the apparatus, an increase in the flux in the receiver A induces a voltage in the secondary winding S, which is in opposition to the normal voltage applied to the secondary circuit by battery H, this opposing voltage at a given speed being very nearly proportional to the increase in the flux in the receiver core. Still referring to Fig. 2, it will be seen that the distance d², representing the increase in 100 flux caused by the second inductor, is shorter than the distance d¹, representing the increase of flux caused by the first inductor. Similarly, the increase of flux due to passing further successive inductors will be successively less until the point is reached at which the flux changes between the same two values each time. It is evident, therefore, that the opposing voltage induced in the secondary winding at a given speed, due to passing an 105 active inductor, is greatest directly after the train-carried apparatus has been re-set. The operation of the valve magnet C by an active inductor depends on the reduction in the current in relay G due to the voltage induced in the secondary winding S. For example, if the holding current through the relay G is 110 60 milliamperes and the relay releases at 20 milliamperes, the reduction in current in the secondary circuit due to the receiver passing 115

an active inductor must be at least 40 milliamperes. This reduction, however, is a function of the speed of the receiver, the approximate character of the relation between speed and current reduction being illustrated by the curve shown in Fig. 3. It is customary to adjust the engine equipment so that it will just operate at a certain minimum speed with normal clearance between receiver and inductor and with normal voltage applied to the train-carried circuits. If this minimum speed is 1.5 miles per hour, then the equipment should always operate to cause a brake application when passing an active inductor at a speed higher than 1.5 miles per hour, but not at a lower speed. This condition of the equipment, however, is affected by hysteresis in two ways. In the first place, assuming that the adjustment of the equipment is made by running over a stop inductor a number of times until it is ascertained that 1.5 miles per hour is the critical speed at which the equipment will operate, then if all engines after adjustment are to be in the same condition, it is evident that the adjustment runs must be made in the same way for all engines. If one engine is adjusted by running over an inductor a number of times, increasing the speed every time the equipment does not operate, until it finally operates at a speed slightly above the critical limit, and if another engine is adjusted by the reverse procedure, that is, starting with speeds above a critical limit and allowing the equipment to operate at every inductor until a value slightly below the critical limit is reached, then it is evident that on account of the hysteresis effect the two engines will show differences in operation when given speed tests under conditions that are actually identical so far as hysteresis is concerned. Consequently, in order to obtain uniform performance on all engines, it is necessary to specify a definite procedure for the adjustment of the engine equipments, so that the receiver will always be in the same hysteresis condition. A considerable number of test runs may be necessary, however, because at low speeds it is difficult to control the engine speed accurately, and if operations must be added to insure a uniform hysteresis condition of the iron in the engine equipment, the process of adjusting the engine equipment is one which consumes considerable time and requires careful attention. In addition to the foregoing, and assuming that uniform adjustment is obtained on all engines, it follows by reference to Fig. 2 that each equipment will be more sensitive to inductors directly after re-set than after passing one or more inductors without being de-energized. Since it is necessary to insure that the equipment under adverse conditions, such as high train voltage and excessive clearance, will not fail to operate at high speeds, and since on the other

hand undesired brake applications due to rails, frogs, etc., must be kept at a minimum, it is readily seen that the hysteresis effect acts to reduce the margin of operation.

The above discussion, although applied specifically to the receiver core, applies also to the relay G. The effect in the relay is more complicated, but the result is of the same nature as the result of the effect in the receiver core. As stated hereinbefore, the relay current diminishes in response to an increase in receiver flux, and, conversely, it increases in response to a decrease in receiver flux. Therefore, every time the receiver runs past an inductor or other iron structure without causing the relay to release, there is first a decrease in the relay flux and then a momentary increase above the normal value. The result of this is a gradual increase in the flux normally present in the relay core, and, consequently, after passing a number of inductors the relay will require a larger reduction in current in order to become de-energized, than immediately after a re-set. The effect on the sensitiveness of the equipment as a whole is smaller than the effect due to hysteresis in the receiver core, but is quite perceptible.

To eliminate these hysteresis effects, I propose to arrange the apparatus so that the iron structures are always in the same hysteresis condition, this being the condition which obtains after the train has passed a few inductors, so that a steady condition in the iron has been reached. To accomplish this, I provide a shunt of relatively low impedance around the magnet C, this shunt comprising an impedance 19 and a normally open contact M which may be closed manually by the engineer or other individual on the engine. When the apparatus is re-set after a brake application, and relay G has closed, the engineer closes switch M for about one second and then opens it again before switch R returns to its normal position. Before the switch M is closed, the flux in the receiver core is at the value represented by the point F₁ in Fig. 2, but upon closing the switch M the primary current increases to a value sufficient to produce a flux corresponding to the point F₂ or a somewhat higher flux, so that the iron is practically in its stable condition and the sensitiveness of the equipment will not change upon passing the next inductor. Considering the relay G, before closing switch M the current flowing through the relay winding is normal, and since the closing of switch M causes a large increase in the receiver flux the relay will release, but, since contact 16 of switch K is now closed, the excess voltage of the auxiliary circuit will immediately close the relay again. When switch M is opened, a considerable reduction in the receiver flux occurs, inducing a momentary excess current in the relay coil, thus increasing the amount of flux normally present in the relay core and

bringing the relay into the same operative condition as that caused by passage of the equipment over several inductors or other iron structures.

5 It follows that when switch M has been closed and is again opened, the equipment is in a condition which is not changed by anything that happens during operation, except by an active trackway inductor. Switch 10 M should be used every time the equipment is re-set, and while the equipment is being tested, but at no other time. If closed accidentally, it will cause the valve magnet to release and so the brakes will be applied.

15 The value of the impedance 19 will depend upon the density of flux in the receiver, and other factors, so that it must be determined experimentally for equipments having different characteristics. I have found that in one 20 commercial form of train control equipment, if the value of the impedance 19 is zero, only a small over-correction of the hysteresis conditions will result.

Referring now to Fig. 4, the apparatus 25 shown in this view is the same as that shown in Fig. 1, except as to the means for controlling the low impedance shunt around the magnet winding C. In Fig. 4, the manually operable switch M has been omitted, and this 30 shunt is controlled by an additional contact 22 on the acknowledging switch K. The low impedance shunt is further controlled by an auxiliary relay R having a back contact 20 and a front contact 21.

35 With the parts in their normal conditions, as shown in the drawing, that is, with relay G and magnet winding C both energized, a first shunt around magnet winding C is closed, which shunt passes from wire 6, 40 through wire 23, winding of relay R, back contact 22-22^a on acknowledging switch K, impedance 19, and wire 24 to wire 7. The proportioning of the parts is such that relay R is then energized, but the resistance of this 45 relay is so high that the shunt path which has just been traced takes an inappreciable amount of current. When the receiver A passes over a trackway inductor B, if contact 18 is closed, the train carried apparatus is not 50 affected in any way. If contact 18 is opened, however, and the engineer acknowledges by operating the acknowledging switch K, auxiliary relay R remains energized because front contact 21 of this relay is connected in multiple with contact 22-22^a so that the opening of the latter contact does not open the circuit for relay R. If the engineer does not acknowledge, however, the opening of relay G will open the circuits for magnet winding 55 C and for relay R, so that the latter relay will become de-energized. When the engineer operates the acknowledging switch K to again pick up relay G, a shunt of low impedance will be closed around magnet winding 60 C, which shunt passes from wire 6, through 65

wire 23, back contact 20 of relay R and the normally open contact 22-22^b on acknowledging switch K, impedance 19 and wire 24 to wire 7. It will be noted that this path does not include the winding of relay R, and, consequently, the shunt path just traced momentarily increases the magnetic flux in the receiver A, and therefore restores this receiver to its normal hysteresis condition. When the acknowledging switch K returns to its normal 75 position, relay R again closes and all parts of the apparatus again occupy the positions in which they are shown in the drawing.

As stated in connection with Fig. 1, the value of the impedance 19 will depend on various factors, and may in some instances be zero.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In a train control system of the type comprising a magnetizable receiver on the train, a primary winding and a secondary winding on said receiver, a circuit for said primary winding including a source of direct current and an impedance, a circuit for said secondary winding including a source of direct current, inductors located in the trackway for co-operation with said receiver, and train governing means controlled by said secondary circuit; the combination with the foregoing instrumentalities of a normally open shunt of relatively low impedance around said impedance in said primary circuit, for eliminating the effect of hysteresis in the core of said receiver, and manually operable means for closing said shunt.

2. In a train control system of the type comprising a magnetizable receiver on the train, a primary winding and a secondary winding on said receiver, a circuit for said primary winding including a source of direct current and an impedance, a circuit for said secondary winding including a source of direct current, inductors located in the trackway for co-operation with said receiver, and train governing means controlled by said secondary circuit; the combination with the foregoing instrumentalities of manually operable means located wholly on the train for momentarily increasing the magnetic flux in said receiver and thereby eliminating the effect of hysteresis in the core of said receiver.

3. In a train control system of the type comprising a magnetizable receiver on the train, a primary winding and a secondary winding on said receiver, a relay, a circuit for said primary winding including a source of direct current and a front contact of said

relay and a magnet winding, a circuit for said secondary winding including the winding of said relay as well as a front contact of the relay and a portion of said primary winding and said magnet winding, inductors 5 located in the trackway for co-operation with said receiver, and train governing means controlled by said magnet winding; the combination with the aforesaid instrumentalities 10 of a normally open shunt of relatively low impedance around said magnet winding, and manually operable means for closing said shunt.

4. In a train control system of the type comprising a magnetizable receiver on the train, a primary winding and a secondary winding on said receiver, a relay, a circuit for said primary winding including a source of direct current and a front contact of said relay and a magnet winding, a circuit for said secondary winding including the winding of said relay as well as a front contact of the relay and a portion of said primary winding and said magnet winding, inductors located in the trackway for co-operation with said receiver, and train governing means controlled by said magnet winding; the combination with the aforesaid instrumentalities of manually operable means wholly on the train for momentarily increasing the magnet flux in said receiver.

5. In a train control system of the type comprising a magnetizable receiver on the train, a primary winding and a secondary winding on said receiver, a circuit for said primary winding including a source of direct current and an impedance, a circuit for said secondary winding including a source of direct current, inductors located in the trackway for co-operation with said receiver, and train governing means controlled by said secondary circuit; the combination with the foregoing instrumentalities of a manually operable circuit controller having a normally closed contact and a normally open contact, an auxiliary relay having front and back contacts, a shunt path around said impedance including the winding of said auxiliary relay and said normally closed contact, and a second shunt path around said impedance including a back contact of said auxiliary relay and said normally open contact.

6. In a train control system of the type comprising a magnetizable receiver on the train, a primary winding and a secondary winding on said receiver, a circuit for said primary winding including a source of direct current and an impedance, a circuit for said secondary winding including a source of direct current, inductors located in the trackway for co-operation with said receiver, and train governing means controlled by said secondary circuit; the combination with the foregoing instrumentalities of a manually operable circuit controller having a

normally closed contact and a normally open contact, an auxiliary relay having front and back contacts, a shunt path around said impedance including the winding of said auxiliary relay and said normally closed contact, 70 a second shunt path around said impedance including a back contact of said auxiliary relay and said normally open contact, and a branch for said first shunt path around the normally closed contact said branch including a front contact of said auxiliary relay. 75

7. In a train control system of the type comprising a magnetizable receiver on the train, a primary and a secondary winding on said receiver, a main relay, a circuit for said primary winding including a source of direct current and a front contact of said relay as well as a magnet winding, a circuit for said secondary winding including the winding of said relay as well as a front contact on said relay, and train governing means controlled by said magnet winding; the combination with the aforementioned instrumentalities of manually operable means wholly on the train for momentarily increasing the magnetic flux in said receiver and thereby eliminating the effect of hysteresis in the cores of said receiver and said relay.

8. In a train control system of the type comprising a magnetizable receiver on the train, a primary and a secondary winding on said receiver, a main relay, a circuit for said primary winding including a source of direct current and a front contact of said relay as well as a magnet winding, a circuit for said secondary winding including the winding of said relay as well as a front contact of said relay, train governing means controlled by said magnet winding, and an acknowledging switch having normally open contacts connected in shunt around the front contacts of said main relay in the circuits for said primary and secondary windings; the combination with the aforementioned instrumentalities of means controlled by said acknowledging switch when operated to close its normally open contacts for momentarily increasing the magnetic flux in said receiver and thereby eliminating the effect of hysteresis in the cores of said receiver and said main relay. 115

9. In a train control system of the type comprising a magnetizable receiver on the train, a primary and a secondary winding on said receiver, a main relay, a circuit for said primary winding including a source of direct current and a front contact of said relay as well as a magnetic winding, a circuit for said secondary winding including the winding of said relay as well as a front contact of said relay, train governing means controlled by said magnet winding, and an acknowledging switch having normally open contacts connected in shunt around the front contacts of said main relay in the circuits for said primary and secondary windings; the 130 120 125 130

- combination with the aforementioned instrumentalities of additional normally closed and normally open contacts on said acknowledging switch, an auxiliary relay having front and back contacts, a shunt path around said magnet winding including the winding of said auxiliary relay and said additional normally closed contact, a second shunt path around said magnet winding including a back contact of said auxiliary relay and said additional normally open contact, and a branch for said first shunt path around the normally closed acknowledging switch contact therein, said branch including a front contact of said auxiliary relay.
10. In a train control system of the type comprising a magnetizable receiver on the train co-operating with trackway inductors, the combination therewith of means located wholly on the train for momentarily increasing the magnetic flux in said receiver and thereby eliminating the effect of hysteresis in the core of the receiver.
15. In a train control system of the type comprising a magnetizable receiver on the train, a winding on said receiver, and a circuit including said winding and a source of current as well as a train governing device, the combination therewith of means located wholly on the train for momentarily increasing the magnetic flux in said receiver and thereby eliminating the effect of hysteresis in the core of the receiver.
20. In testimony whereof I affix my signature.
